SYSTEM FOR FORMING AND STORING
HYDROCARBON HYDRATES

Arthur J. L. Hutchinson, Los Angeles, Calif., assignor to The Fluor Corporation, Ltd., Los Angeles, Calif., a corporation of California

Application August 15, 1941, Serial No. 407,036

18 Claims. (Cl. 260—676)

This invention relates to improved methods for treating and storing normally volatile hydrocarbons such as natural gas, refinery gases and the like, and is a continuation-in-part of my copending application Serial No. 392,186, filed May 6, 1941, on Fractionation of hydrate-forming hydrocarbons.

The customary method of maintaining these gases for fuel and other industrial purposes, is to store them in gaseous phase, using large volume holders characterized by their great size and space requirements, as well as their susceptibility to rupture leading to immediate and violent combustion of liberated gas. Another method, more recently commercialized, involves liquefaction of the gases and storing the hydrocarbons in liquid phase. That type of system is characterized by the expensive and special steel containers required to withstand pressure at extremely low temperatures, and even higher equipment and operating costs necessary for refrigeration of "liquid" gas at temperature sufficiently low, say in the neighborhood of minus 160° F., to maintain the hydrocarbon vapor pressures within practicable limits.

The general method employed according to the invention involves conversion of the hydrocarbons into their solid hydrates, i. e. water-addition products, which are characterized by their capacity for stabilization at considerably higher temperatures (and even proportionately less refrigerating costs) than those required for liquid phase storage for corresponding vapor pressures of the stored materials. A further important advantage of this method is that the hydrates, as such, are not combustible, and that while liberated hydrocarbons resulting from dissociation of the hydrates will burn, their rate of liberation ordinarily is sufficiently slow to prevent violent combustion or explosion. Not only do the hydrates lend themselves with particular advantage to storage under favorable temperature and pressure conditions to maintain the hydrocarbons in non-explosive condition, but they also permit ready liberation of the hydrocarbons for use from storage, and separation of moisture from the liberated gas by reason of the fact that the hydrates can be dissociated simply by reduced pressure or increased temperature controls, or a combination of both, and their water content remains as residue.

Among different objects, the present invention aims to provide certain improvements and innovations with respect to the conditions and method by which the hydrates initially are formed

for storage or other disposal, and the manner in which the formed hydrates may be transferred from one zone to another, and specifically from the converter or hydrate forming zone to a storage chamber or other vessel. It is desirable that the hydrates be formed in particle or crystal sizes better adapting the hydrates to transmission in a carrier medium, and to reduce the hydrate particle sizes to an extent permitting maximum quantity storage in a volume of given size. For the purpose of causing the hydrates to form as small crystals, I propose to contact the gas and water in the presence of a non-aqueous carrier, preferably by first emulsifying the water with the carrier to reduce the water to a state of fine particle dispersion within the carrier. In addition to its function as a dispersing medium for the water, the non-aqueous carrier also serves effectively as a heat absorbing medium (i. e. for heat of hydrate formation) and as a flushing medium to constantly remove the hydrates from the conversion zone, and at the rate at which they are formed. The carrier further serves effectively as a transmission medium for the hydrates in conveying them, for example, from the converter to the storage zone. As will later appear, circulation of the carrier liquid between the two zones provides a simple method for continuous withdrawal of the hydrates from the converter, and continuous accumulation of the hydrates in the storage zone.

Certain aspects of the invention are to be regarded as independent of any particular disposition to be made of the hydrates removed from the converter in the carrier liquid stream. As explained, the hydrates may be maintained in storage for subsequent liberation and use of the hydrocarbons at any subsequent time. Another adaptation of the invention is for purposes of a gas compression system adapted to replace and serve the purposes of the relatively expensive compressor plants now in operation. It is made possible by the invention to dispense entirely with mechanical compression of the gas, by the simple expedient of converting relatively lower pressure gas into hydrated form, transferring the hydrates to what may be termed a pressure generator, and therein heating the hydrates to release the gas at relatively high pressure, all in a continuous or intermittent type operation and with little required mechanical equipment.

The above features and objects of the invention, as well as various additional aspects, will be understood to better advantage from the following detailed description of certain typical and

illustrative systems. Throughout the description reference is had to the accompanying drawings, in which:

Fig. 1 is a general and diagrammatic view illustrative of the invention;

Fig. 2 is a similar view showing an adaptation of the hydrate forming and storage system for treating uncondensed refinery gases; and

Fig. 3 illustrates a system for utilizing the hydrated condition of the gas for high pressure gas generation.

Referring first to Fig. 1, the gas stream introduced through line 10 to the converter 11 ordinarily will comprise hydrocarbons predominantly within the range of methane, ethane, the propanes and butanes, together with fixed gases such as hydrogen sulphide, carbon dioxide, helium, oxygen, and nitrogen. Depending upon its normal condition, the gas may or may not be precooled before its introduction to the converter, although some cooling of the gas ordinarily will be required to bring the gas and water mixture in the converter within the temperature range at which hydrate formation will occur under the existing pressure. The pressure in the converter may be held between about 400 to 650 lbs. per sq. in., and the temperature of the gas and water or emulsion inlet streams regulated so that, with or without additional cooling, the temperature in the converter will range between about 35 to 40° F. Water introduced to the converter through line 12 may be passed through cooler 13, or bypass line 14, and suitably discharged into the gaseous atmosphere within the converter in finely divided form or mist, as through spray nozzles 15. It is desirable that the water and gas be brought into intimate contact for the dual purposes of assuring their effective interaction in forming the hydrates, and to cause the hydrates to form as small crystals better adapted to suspension in the carrier medium and to close packing in the storage zone. Dispersion of the water or emulsion as spray or mist in an atmosphere of the gas, establishes a condition suitable for the accomplishment of these purposes in the initial formation of the hydrates.

As previously indicated, the water may be introduced to the converter alone or in dispersed or emulsified condition in a non-aqueous carrier liquid which may serve both to maintain the moisture initially in a state of fine particle division or dispersion, and to provide a liquid medium within which solid hydrates are carried out of the converter to the storage zone, as will later appear. Accordingly, the liquid introduced through line 12 may consist of around 1½ to 1 parts of water in a non-aqueous liquid carrier, preferably one immiscible with water so that the latter is present in at least substantially emulsified condition in the carrier. While any suitable carrier liquid may be used, I preferably employ a mineral oil distillate or fraction such as kerosene, or a relatively heavy kerosene distillate. Mineral oil carrier is particularly suitable by reason of its availability, ease of handling in the circulation system, and its adaptability to rather close adjustment of its specific gravity. In order to maintain the hydrates most effectively suspended in the carrier during transference of the hydrates from the converter to the storage zone, it is desirable that the specific gravity of the carrier be adjusted to correspond closely or substantially to the specific gravity of the hydrates. The mineral oil fraction may be particularly selected for specific gravity correspondence with

the hydrates, and, as stated, a kerosene distillate appears best suited for the purpose.

Rapid formation of the hydrates results from contacting the gas and moisture in the converter, the solid hydrates settling to the base of the converter and being carried through the outlet 16 to the discharge line 17. Fixed gases and unconverted hydrocarbons are withdrawn through line 18, the inlet 18a of which is shielded by a baffle 19 to prevent line 18 from becoming clogged by hydrate formation within its inlet. The gases discharged through line 18 may again be treated in a second stage converter (not shown) in the manner described for the treatment of the raw gas in line 10, or given any other suitable disposal. With provision made for sufficient time and intimacy of contact between the gas and water, it is possible to convert into hydrates and in a single stage, substantially all hydrocarbon constituents of the gas capable of hydration.

Various methods may be employed for preventing congesting accumulations of hydrates tending to remain in the converter, as by building up on its walls. By passing a suitable heating fluid through the chamber jacket 181 (which otherwise may serve as a heat insulating medium for the chamber), the chamber wall may be warmed to a temperature at which the hydrates contacting the wall will melt and thus cause all the hydrates to gravitate through the outlet 16 to the discharge line. Hydrate accumulations may also be prevented by continuously flushing the wall of the converter with a suitable liquid, preferably the non-aqueous hydrate carrier. Thus, a stream of the carrier being pumped through line 20 into the upper interior of the converter, may be sprayed downwardly and directly against the chamber wall through an annular nozzle 21.

It will be understood that a circulation of the carrier liquid in such manner as to convey the hydrates from the converter to the storage zone, may be maintained in any suitable manner, and, more specifically, by the introduction of the carrier liquid directly into the converter, as explained, or in a circulating system which receives the hydrates after their discharge from the converter. According to the typical system illustrated, the hydrates removed through the converter outlet 16 into the discharge line 17 are met by a stream of the carrier liquid being pumped through line 22 and discharged through nozzle 23 into conduit 17, and acting to withdraw and entrain by ejector action, the hydrates being produced in the converter.

The hydrate-carrier stream flows through line 24 into a suitable storage zone 25, shown typically as a vessel or tank 26, which for hydrate storage purposes will have considerably large volume. Within storage zone 25 the carrier liquid is separated from the hydrates, as by depositing the latter on the foraminous floor 27 through which the carrier liquid drains to the outlet 28. The liquid then recirculates through line 28 to be forced by pump 29 through a cooler 30 and then to line 22, the primary purpose of the cooler being to remove from the carrier liquid, heat of formation of the hydrates generated in the converter 11. It may be mentioned that the heat of hydrate formation may be removed elsewhere in the system, as by passing a cooling fluid through the converter jacket 181 or by a heat exchanger in the discharge line 17.

The hydrates are maintained in the storage zone 25 under stabilizing temperature and pres-

sure conditions which, by reason of the properties and vapor pressure characteristics of the hydrates, do not necessitate the high pressure required in the converter 11. Accordingly, beyond valve 32 in the discharge line and in the storage zone, the pressure may be reduced sufficiently low to obviate necessity for using high pressure or special steel storage vessels (as required, for example, in low temperature, liquid phase storage). Typically, the hydrate storage pressure may be around 25 lbs. per sq. in., or even lower, depending upon the most economical balance of decreasing pressure, and increasing refrigeration costs.

The hydrate storage temperature required to keep the hydrate vapor pressure desirably low, may be maintained in any suitable manner, as by passing a cooling or refrigerating fluid in heat transferring relation with the stored hydrates. For example, cooling fluid introduced through line 33 may be circulated through line 34 in the storage vessel jacket 35 to the outlet line 36, or the circulation may occur through a cooling coil 37 within the storage zone itself. It is contemplated that the hydrate carrier liquid may in some instances be employed as the storage zone cooling medium, with or without cooling of the carrier liquid in addition to that occurring in heat exchanger 30. Thus, the carrier liquid is shown to be capable of circulation through line 37 into the storage chamber jacket 35, or cooling coil 37, thence to be recirculated through line 38. As will be understood, the hydrates may be maintained indefinitely in the storage zone.

When it is desired to release the hydrocarbons from the storage zone for use as fuel gas or other purposes, dissociation of the hydrates may be effected by either pressure reduction, or heating, or a combination of both. By opening the normally closed valve 40 in the outlet line 41, the pressure may be reduced sufficiently to cause dissociation of the hydrates without heating, or at least supplying any substantial amount of heat. On the other hand, the stored hydrates may be heated to release the hydrocarbons at a pressure above their normal storage pressure, as will be more particularly dealt with in describing the embodiment of the invention shown in Fig. 3. Usually it is preferred to heat the stored hydrates in a manner that will assure substantially uniform dissociation of all the hydrates, so that the released gas will contain the hydrocarbons in substantially their normal relative proportions. For this purpose, a heating fluid may be introduced through line 33 and circulated either through the storage chamber jacket 35 or coil 37. The heating fluid may be circulated through lines 38 and 34 by pump 28 (the exchanger 30 in this instance serving as a heater), and the hydrate carrier liquid may be used as the heating medium. Instead of thus indirectly transferring heat from the heating fluid to the hydrates, the heating fluid may be circulated through the storage zone in direct contact with the hydrates, as by way of lines 42, 24, and the drain line 28. No problem of moisture separation from the liberated hydrocarbons is involved, due to the fact that the hydrate water of combination remains in the storage zone (vaporization of the hydrates having the effect of cooling the residual water and thereby preventing its vaporization).

Fig. 2 illustrates the described hydrate conversion and storage system in conjunction with a refinery producing uncondensed hydrocarbons 75

in the tail gas stream, which are capable of conversion to hydrates and storage in their hydrated form. Fractionating column 44 may be taken as the final fractionating zone in a straight run or cracking plant, and in which the vapors leaving the fractionating column through line 45 are subjected to final condensation in condenser 46. Gasoline condensate is collected in the receiver 47, from which the fixed gases and uncondensed hydrocarbons are discharged through line 48. These gases then are compressed by the compressor 49 to a pressure, e. g. 400 to 650 lbs. per sq. in., at which the hydrates will form in the converter 11. After passage through the cooler 50, the gas enters the converter through line 10a, all as previously described.

Fig. 3 illustrates a further variational adaptation of the invention for the dual or individual purposes of forming and storing the hydrates, and releasing the gaseous hydrocarbons from the storage zone at relatively high pressures as compared with the initial or normal pressure of the gas. According to this system, advantage is taken of the hydrate-forming properties of the hydrocarbons to employ the transitions of gas-to-hydrate, and then dissociation into gas, to serve essentially the same purposes as a gas mechanical compressor system, but without the costly equipment and operating expenses required for mechanical gas compression.

Here the converter 53 is shown as a vertically extending column to which the hydrocarbon gas is introduced through line 54 to flow upwardly within the converter, countercurrently to a stream of water, or water and carrier emulsion, fed to the converter through line 55 and sprayed downwardly from the nozzles 55a. Fixed and non-hydrated gases are intermittently or continuously withdrawn from the converter through the valved line 56. The solid hydrates leave the base of the converter through line 57, and are discharged through heat exchanger 59 into the vessel 60 within which the hydrates may be contained temporarily, or stored for an extended length of time. In this instance the vessel 60 is intended to serve also as a pressure generator and therefore will have sufficient strength to withstand high pressures. The carrier liquid separated from the hydrates in vessel 60 is recirculated by its own pressure to the converter through line 61, heat exchanger 59 line 55 and the cooler 62, makeup water and any excess carrier liquid being supplied through line 63. The hydrates and carrier liquid from vessel 53 are pumped by pump 58 through line 57, heat exchanger 59 into pressure generator 60. It is understood that in normal operation pressure generator 60 would be maintained at a higher pressure than converter 53. It will be understood that the storage vessel or pressure generator 60 will be provided with any suitable means, such as described, with reference to Fig. 1, for maintaining the stored hydrates at desirably low temperature (if vessel 60 is to serve as storage), until such time as the hydrocarbons are to be released.

Employing a heating coil 64, or any other suitable source of heat, the temperature of the hydrates in vessel 60 may be raised above their critical temperature of formation, whereupon they will dissociate and release the hydrocarbons in gaseous phase, and also increase the pressure of the hydrocarbon gas, as additional hydrates are dissociated in the chamber, to as high a value as may be desired, for example to 1,000

lbs. per sq. in., or above. A corresponding back pressure may be maintained by a suitable control valve 65 permitting the gas to be released through line 66 under high pressure and for whatever purpose the high pressure gas may be needed. Suitable means, such as a system of baffles 64, may be used to separate liquid entrainment from the outlet gas.

It will be observed that transference of hydrates from the converter to the pressure generator, and the release of high pressure gas from the generator, may proceed continuously, or intermittently. That is to say, the hydrate-carrier stream may be continuously circulated to maintain continuous delivery of hydrates to the pressure generator, and the hydrates therein may continuously be heated to cause their dissociation into high pressure gas. When operated in this manner, the continuous withdrawal of carrier liquid from the base of the generator may be controlled by a suitable valve 67 operated by the conventionally illustrated float mechanism 68, which maintains a minimum level of the liquid in the base of the pressure vessel. Excessive water concentrations in the carrier oil, and resulting from residual water after vaporization of the hydrocarbons in the pressure generator, may be suitably removed, as by a separator diagrammatically shown at 72.

Operating on an intermittent cycle, the pressure vessel 60 may more or less completely be filled with hydrates, valves 69 and 70 closed (the float operated valve 67 in this instance not being used), and the accumulated hydrates then heated to generate and release the hydrocarbon gas under the desired high pressure.

I claim:

1. The process that includes, converting normally gaseous hydrate-forming hydrocarbons into their solid hydrates in a hydrate forming zone, removing the hydrates from said zone in a carrier liquid into a second zone, and separating the carrier liquid from the hydrates.

2. The process that includes, converting normally gaseous hydrate-forming hydrocarbons into their solid hydrates in a hydrate forming zone, removing the hydrates from said zone in a carrier liquid into a second zone, separating the carrier liquid from the hydrates, and maintaining the hydrates in said second zone under stabilizing temperature and pressure conditions.

3. The process that includes, converting normally gaseous hydrate-forming hydrocarbons into their solid hydrates in a hydrate forming zone, removing the hydrates from said zone in a carrier liquid into a second zone, separating the carrier liquid from the hydrates, and recirculating the separated carrier liquid to remove additional hydrates from said forming zone.

4. The process that includes, converting normally gaseous hydrate-forming hydrocarbons into their solid hydrates in a hydrate forming zone, removing the hydrates from said zone in a water-immiscible carrier liquid into a second zone, and separating the carrier liquid from the hydrates.

5. The process that includes, converting normally gaseous hydrate-forming hydrocarbons into their solid hydrates in a hydrate forming zone, removing the hydrates from said zone in a water-immiscible carrier liquid into a second zone, separating the carrier liquid from the hydrates, and introducing a mixture of the sep-

arated carrier liquid with water into said hydrate-forming zone.

6. The process that includes, converting normally gaseous hydrate-forming hydrocarbons into their solid hydrates in a hydrate forming zone, removing the hydrates from said zone in a water-immiscible carrier liquid into a second zone, separating the carrier liquid from the hydrates, and recirculating the separated carrier liquid to remove additional hydrates from said forming zone.

7. The process that includes, converting normally gaseous hydrate-forming hydrocarbons into their solid hydrates in a hydrate forming zone, removing the hydrates from said zone in a water-immiscible carrier liquid into a second zone, separating the carrier liquid from the hydrates, storing the hydrates in said second zone, and later dissociating the stored hydrates.

8. The process that includes, converting normally gaseous hydrate-forming hydrocarbons into their solid hydrates in a hydrate forming zone, and removing the resulting hydrates from said zone in a water-immiscible carrier liquid.

9. The process that includes, converting normally gaseous hydrate-forming hydrocarbons into their solid hydrates in a hydrate forming zone, and removing the resulting hydrates from said zone in a stream of mineral oil.

10. The process that includes, converting normally gaseous hydrate-forming hydrocarbons into their solid hydrates within a hydrate forming zone by contacting the hydrocarbons with a preformed intimate mixture of water and a water-immiscible carrier liquid, the water in said mixture being in finely divided condition.

11. The process that includes, converting normally gaseous hydrate-forming hydrocarbons into their solid hydrates within a hydrate forming zone and in the presence of a water-immiscible carrier liquid containing small water particles, and removing the resulting hydrates from said zone to a second zone in a stream of said carrier liquid.

12. The process that includes, converting normally gaseous hydrate-forming hydrocarbons into their solid hydrates within a hydrate forming zone by contacting said hydrocarbons with a preformed emulsion of water and a water-immiscible carrier liquid in which the water is in finely divided condition.

13. The process that includes, converting normally gaseous hydrate-forming hydrocarbons into their solid hydrates within a hydrate forming zone by contacting said hydrocarbons with an emulsion of water and a water-immiscible carrier liquid, and removing the resulting hydrates from said zone to a second zone in a stream of said carrier liquid.

14. The process that includes, converting normally gaseous hydrate-forming hydrocarbons into their hydrates within a hydrate forming zone by contacting said hydrocarbons with water, introducing to said zone a water-immiscible carrier liquid, removing the hydrates from said zone in a stream of the carrier liquid into a second zone maintained under relatively low pressure, separating the carrier liquid from the hydrates, and recirculating the separated carrier liquid through a cooling zone into said hydrate forming zone.

15. The process that includes, converting normally gaseous hydrate-forming hydrocarbons into their hydrates within a hydrate forming zone by contacting said hydrocarbons with water

in the presence of mineral oil carrier liquid, removing the hydrates from said zone in a stream of the carrier liquid into a second lower pressure zone, separating the carrier liquid from the hydrates, storing the hydrates in said second zone under stabilizing temperature and pressure conditions, and later heating and dissociating the hydrates in said second zone to release the hydrocarbons for use.

16. The process of developing hydrocarbon gas under high pressure that includes, converting relatively low pressure normally gaseous hydrate-forming hydrocarbons into their solid hydrates within a hydrate-forming zone, continuously pumping a mixture of liquid and the resulting hydrates into a second higher pressure zone, and heating and dissociating the hydrates in said second zone to release the hydrocarbons at a pressure higher than the pressure of the hydrocarbons before their conversion to hydrates.

17. The process of developing hydrocarbon gas under high pressure that includes, continuously

converting relatively low pressure normally gaseous hydrate-forming hydrocarbons into their solid hydrates within a hydrate-forming zone, continuously pumping a mixture of mineral oil carrier liquid and the resulting hydrates into a second higher pressure zone, and continuously heating and dissociating the hydrates in said second zone to release the hydrocarbons at a pressure higher than the pressure of the hydrocarbons before their conversion to hydrates.

18. The process of developing hydrocarbon gas under high pressure that includes, converting relatively low pressure normally gaseous hydrate-forming hydrocarbons into their solid hydrates within a hydrate-forming zone, transferring the resulting hydrates into a second zone in a stream of carrier liquid, and heating and dissociating the hydrates in said second zone to release the hydrocarbons at a pressure higher than the pressure of the hydrocarbons before their conversion to hydrates.

ARTHUR J. L. HUTCHINSON.
